X-RAY TUBE HOUSING

Cornelius Keith Vandervelden, Arlington Heights, and
Theodore Prisland, Evanston, Ill., assignors to Litton
Medical Products, Inc., Des Plaines, Ill., a corporation
of Delaware

Filed Mar. 28, 1969, Ser. No. 16,502

Term of patent 14 years

Int. Cl. D24—02

U.S. Cl. D83—1

FIGURE 1 is a front perspective view of an X-ray tube housing showing our new design;

FIGURE 2 is a rear perspective view thereof;

FIGURE 3 is a side elevation as seen from the right of FIG. 2;

FIGURE 4 is a side elevation as seen from the left of FIG. 2; and

FIGURE 5 is a top plan view thereof.

We claim:

The ornamental design for an X-ray tube housing, as shown.
